Patented June 30, 1964

198,551

RAPID TRANSIT CAR

James A. Gardner, Glenside, and Lewis F. Reynolds,
Meadowbrook, Pa. (both % The Budd Co., 2450
Hunting Park Ave., Philadelphia 32, Pa.)

Filed Oct. 30, 1963, Ser. No. 77,206

Term of patent 14 years

(Cl. D66—1)

Fig. 1

Fig. 2

Fig. 4

Fig. 3

FIG. 1 is a perspective view of a rapid transit car embodying our new design;

FIG. 2 is a side elevational view thereof;

FIG. 3 is an end elevational view thereof; and

FIG. 4 is an enlarged sectional view taken on lines 4—4 of FIG. 2.

The essential features of our new design reside in the portions shown in full lines in the drawing.

The side not shown is substantially the same in appearance as the side shown.

We claim:

The ornamental design for a rapid transit car, as shown and described.
